UNITED STATES PATENT OFFICE.

LELAND A. COLBY, OF CLIO, CALIFORNIA.

CROSSCUT-SAW SET.

1,115,508.

Specification of Letters Patent.

Patented Nov. 3, 1914.

Application filed August 24, 1910. Serial No. 578,636.

To all whom it may concern:

Be it known that I, LELAND A. COLBY, a citizen of the United States, residing at Clio, in the county of Plumas, State of California, have invented certain new and useful Improvements in Crosscut-Saw Sets; and I do hereby declare the following to be a full, clear, and exact description of the invention, such as will enable others skilled 10 in the art to which it appertains to make and use the same.

This invention relates to improvements in saw sets, more particularly of the class wherein the setting action is produced by 15 the blow of a hammer upon a set pin, and has for one of its objects to improve the construction and increase the efficiency and utility of devices of this character.

Another object of the invention is to provide a simply constructed device of this 20 character wherein provision is made for adjusting the anvil to increase or decrease the extent of the "set".

Another object of the invention is to provide a device of this character having adjusting means whereby the device may be 25 adapted to the size of the teeth of the saw, so that the improved device may be employed without structural change upon saws 30 having teeth of different sizes.

With these and other objects in view, the invention consists in certain novel features of construction as hereinafter shown and described and then specifically pointed out in 35 the claims; and, in the drawings illustrative of the preferred embodiment of the invention, Figure 1 is a side elevation, partly in section, of the improved device, Fig. 2 is an elevation from the feed end, Fig. 3 is a plan 40 view with the standard in section on the line 3—3 of Fig. 1, Fig. 4 is a transverse section on the line 4—4 of Fig. 3 looking in the direction of the arrow.

The improved device comprises a base or 45 bed 10 from which a standard 11 arises, the base and standard being preferably cast in one piece and provided with lugs 12 by which the base and its standard may be secured to a bench or other support, if required.

The standard 11 is provided with a forwardly directed extension 13 at its upper end, and with a bore 14 to receive a set pin 15. The bore 14 is counterbored at its upper 50 end as shown at 16 and the set pin 15 is provided with an enlarged head 17 which oper-

ates in the counterbore. A spring 18 is disposed within the counterbore portion 16 and bears upwardly against the enlarged portion 17, and thus maintains the set pin yieldably in its upward position. The enlarged portion 17 is provided with a longitudinal slot 19, and extending through the extension 13 of the standard and likewise through the slot is a stop pin 20 the pin operating to limit the movement of the set pin and its enlarged head, while at the same time permitting the downward movement of the same.

The base portion 10 is provided with a relatively large longitudinal slot or opening 21, having guide grooves or channels 22—23 in its inner sides, and slidably disposed within the slot 10 is an anvil carrying member 24, the member 24 being provided with ribs 25—26 engaging in the guide channels 22—23. By this means the member 24 is 70 slidable within the slot 21 and is retained in position by the guide ribs. Bearing upon the upper face of the member 24 is a plate 27, preferably of hardened steel, and with one end extending forwardly of the member 24, as shown, and with its terminal reduced laterally as shown at 28, the reduced portion likewise having its upper face inclined, as shown. The reduced portion of the plate 27 forms the "anvil" of the improved device, and is located directly beneath the set pin 15, the latter having its lower end inclined as shown at 29 to correspond to the required set of the teeth. It 75 will be noted that the slot 21 of the base 10 terminates short of the anvil 28 so that the latter bears constantly upon a solid portion 80 of the base, for obvious reasons.

At its outer end the base 10 is provided with a transverse plate 30, and mounted for rotation in this plate is a screw 31 having a wing nut 32 upon its outer end to enable the screw to be rotated, the portion 31 engaging in a threaded aperture in the member 24 so that the latter may be adjusted longitudinally of the base by rotating the screw 31 by its wing nut 32. By this means 100 the position of the anvil portion 28 of the plate 27 may be adjusted as required.

Bearing around the standard 11 is a U-shaped frame 33, the forward ends of the member 33 being provided with transverse extensions 34—35 which form gage plates 110 to control the position of the teeth of the saw relative to the set pin. The gage plates

34—35 it will be noted are in alinement transversely of the base 10 and are designed to control the position of the saw teeth, as hereinafter explained.

5   Mounted for rotation in the frame 33 at the rear side of the standard 11 is a screw 36 having a wing nut 37 to enable the screw to be rotated, the screw being tapped into the standard as shown. By this means it will 10 be obvious that by rotating the screw 36 by its wing nut 37, the frame 33 and its gage members 34—35 may be adjusted to correspond to the required position of the saw teeth relative to the anvil and set pin. 15   When the saw teeth are to be set the anvil 28 and the members 34—35 are adjusted to correspond to the teeth of a saw, and the latter laid over the plate 27 with the lower side of the tooth which it is desired to set 20 located above the anvil 28 and with the points of the teeth against the gage members 34—35. A blow is then imparted to the enlarged head 17 of the set pin with the result of driving the set pin upon the saw tooth 25 and bending the same over the inclined upper face 28 of the anvil, the set pin being immediately returned to its upper position by the action of the spring 18. The saw is then moved along to bring another tooth 30 into position and the operation repeated.

The improved device is simple in construction, can be inexpensively manufactured and of any required strength and

readily adapted without structural changes to saw teeth of varying sizes and forms. 35 The plate 27 being separate from the supporting member 24 can be readily renewed when broken or impaired without discarding the remaining portions of the device.

What is claimed is:—

40   A saw set comprising a base provided with a long slot opening through its forward end, and having grooves in the inner faces of its resultant furcations, a removable carriage slidably mounted between the furcations and having longitudinal ribs engaged in the grooves, a plate secured to the outer ends of the furcations and extending across the space there-between, an adjusting screw mounted in the plate and engaged with the carriage to move the latter, a removable anvil attached upon the carriage and extending beyond the inner end of the carriage to project over and rest upon the base, for the purpose of making a sound 45 foundation for the saw teeth, means mounted above the anvil for setting saw teeth with respect to the anvil head, and means for gaging the edge of a saw with respect to the setting means.

50   In testimony whereof, I affix my signature, in presence of two witnesses.

60   LELAND A. COLBY.
